UNITED STATES PATENT OFFICE.

SAMUEL H. SNAVELY, OF WASHINGTON, DISTRICT OF COLUMBIA, ASSIGNOR
OF ONE-FOURTH TO FREDERIC W. RITTER, JR., OF SAME PLACE.

CURTAIN-FIXTURE.

SPECIFICATION forming part of Letters Patent No. 481,978, dated September 6, 1892.

Application filed January 27, 1892. Serial No. 419,447. (No model.)

To all whom it may concern:

Be it known that I, SAMUEL H. SNAVELY, a citizen of the United States, residing at Washington city, District of Columbia, have invented certain new and useful Improvements in Curtain-Fixtures; and I hereby declare the following to be a full, clear, and exact description of the same, reference being had to the accompanying drawings, wherein—

10 Figure 1 is an elevation of a portion of a window, showing the fixtures and manner of attaching the same to the window. Fig. 2 is a transverse section on the line $\alpha\alpha$ of Fig. 1, illustrating the construction of the brackets, whereby the same are adapted for use with frames of different depths and curtains which are wider than the sash. Fig. 3 is a detached perspective view of the bracket, showing the construction whereby the arm of the bracket is rendered capable of adjustment to compensate for any irregularity in the height of the bracket shoe or socket. Fig. 4 is a face view of the outer section of the bracket. Fig. 5 is a back view of said outer section. Fig. 6 is a face view of the inner section of the bracket or that next to the shoe or socket piece. Fig. 7 is a perspective view of the bracket shoe or socket piece. Fig. 8 is a view of a modification or short-section bracket adapted for use

15 in hanging curtains on windows having inside blinds.

Like symbols refer to like parts wherever they occur.

My invention relates to the construction of brackets for curtain-fixtures, and has for its objects the production of a bracket which shall be adapted to meet the requirements of window-frames of different depths, to compensate for any inequality in the height of bracket-supports, and applicable to windows having either outside or inside blinds.

To this end the main feature of my invention embraces a sectional extensible bracket having means for adjusting and securing the sections so that their longitudinal axes shall intersect, whereby the outer end of the bracket may be set either above or below the inner end thereof.

There are other minor features of invention, all as will hereinafter more fully appear.

The bracket hereinafter described may be applied either to the sash or the frame of a window; but has been especially devised for the upper sash thereof, so that said sash may be lowered to ventilate the rooms without rendering the curtain liable to be whipped out by the incoming air-current or to obstruct the entrance thereof.

I will now proceed to describe my invention so that others skilled in the art to which it appertains may apply the same.

In the drawings, A indicates the window-frame, B the upper, and C the lower sash thereof.

1 indicates a bracket shoe or socket provided with a suitable open slot 2 for the reception of a dovetailed projection on the end of the inner section of the bracket. In casting the dovetailed projection on the inner bracket-section it is necessary to form an incline on the end of said section, as at a' , to facilitate the drawing of said casting, and to compensate for this and insure that the bracket shall stand at right angles to the sash I preferably form the bracket-shoe thicker at the heel, as at a , Fig. 7, so as to give said shoe a wedge form or inclined face. The shoe 1 may be secured to either the frame or sash in any suitable manner.

3 indicates the extensible bracket, of which 3^a is the inner or shoe section, and is provided with a dovetailed projection 4, adapted to enter the slot 2 in the shoe 1, and 3^b is the outer or curtain section, which in the case of the curtains wider than the window-sash will have an elbow, as especially indicated in Figs. 2 and 3. In case the bracket is desired for use with curtains of less width than the sash (or for use with windows having inside blinds) the curtain-sections 3^b will be proportionately shortened and the elbow will be formed on the shoe-section 3^a , as indicated in Fig. 8 of the drawings.

In order to arrange the bracket-sections 3^a 3^b with their longitudinal axes intersecting 95 or said sections at an angle to each other, so as to elevate or depress either or both roller-bearings when desired for purposes of adjustment, I form one of the contacting faces of one section with longitudinal grooves 5 100

and the other at or near its end with projecting points or teeth 6, adapted to enter the grooves 5.

In the drawings I have shown both of the 5 contacting faces of bracket-sections 3^a 3^b provided with said grooves 5 and points 6, as that is the preferred form; but it will be evident to a person skilled in mechanics that a 10 single set of grooves and points placed in the two bracket-sections will suffice for purposes of adjustment.

Each bracket-section is provided with a slot 3^c, through which passes a screw 7 or equivalent means of connecting and clamping the 15 parts together, and in one of said sections I prefer to form a rectangular groove or seat 8 (see Figs. 5 and 8) for the reception of the nut 7^a of said screw 7.

The outer ends of the curtain-sections 3^b 20 are each provided with duplicate journal-bearings 9 and 9^a, whereby the brackets are rendered reversible, or, in other words, the bracket may be used either on the right or left side of the frame at will, and thus accommodate either a right or left hand spring-roller.

The construction of the bracket being substantially of the character hereinbefore specified, the length of the bracket may be adjusted 30 to any given depth of framing by slipping the sections 3^a and 3^b longitudinally on each other, and at the same time any inequality of the height of the shoes 1 (or in case the framing A has sunken at one side) may be provided for by canting the curtain-section either up or down until the points 6 enter the proper grooves 5, after which the nut and screw 7 7^a or other suitable clamp may be tightened to secure the sections 3^a 3^b in the 40 desired position.

Having thus described my invention, what

I claim, and desire to secure by Letters Patent, is—

1. In a curtain-bracket, the combination of two lapping longitudinally-adjustable arm-sections having adjacent corrugated interlocking surfaces which permit said arm-sections to be adjusted longitudinally in a right line and also at an angle to each other and a clamp for securing the parts when adjusted 50 in either position, substantially as and for the purposes specified.

2. The combination, in a curtain-bracket, of two bracket-sections adjustable one on the other, one of said sections provided with longitudinal grooves and one with points or projections adjacent to one end thereof, whereby said sections may be adjusted in a right line or at an angle to each other, substantially as and for the purposes specified.

3. The combination, in a curtain-bracket, of two adjustable sections, each provided on its inner or contacting face with grooves and points, whereby said sections may be adjusted to a right line or at an angle to each other, 65 substantially as and for the purposes specified.

4. In a curtain-bracket, the combination of two longitudinally-slotted extensible arm-sections having adjacent corrugated interlocking surfaces and means for pivotally and adjustably connecting and clamping said arm-sections, substantially as and for the purposes specified.

In testimony whereof I affix my signature, in 75 presence of two witnesses, this 26th day of January, 1892.

SAMUEL H. SNAVELY.
